Primary Examiner — Darlington Ly(74) *Attorney, Agent, or Firm* — Michael Best & Friedrich LLP(57) **CLAIM**

The ornamental design for a power tool, as shown and described.

DESCRIPTION

FIG. 1 is a front perspective view of a power tool showing my new design.

FIG. 2 is an enlarged front perspective view of a portion of the power tool of FIG. 1.

FIG. 3 is a front view of the power tool of FIG. 1.

FIG. 4 is an enlarged front view of a portion of the power tool of FIG. 1.

FIG. 5 is a front perspective view of a power tool according to another embodiment of the invention; and,

FIG. 6 is a first side view of the power tool of FIG. 5.

The portions of the power tool shown in broken lines are included for the purpose of illustrating environment and form no part of the claimed design. The portions of the power tool shown in broken lines having unequal length segments illustrate the boundary of the claimed design and form no part of the claimed design.
